(57) **CLAIM**

The ornamental design for a lens converter, as shown and described.

DESCRIPTION

FIG. 1 is a front view of a lens converter showing my new design;

FIG. 2 is a rear view thereof;

FIG. 3 is a top plan view thereof;

FIG. 4 is a bottom plan view thereof;

FIG. 5 is a left side view thereof;

FIG. 6 is a right side view thereof;

FIG. 7 is a top, front, and left side perspective view thereof; and,

FIG. 8 is a top, front, and left side perspective view thereof, shown in condition of use with a sample environment disclosed in broken lines.

The broken lines depict portions of the lens converter in which the design is embodied that form no part of the claimed design. The broken lines showing a sample environment in FIG. 8 represent environmental structure and form no part of the claimed design.
